CLAIM

The ornamental design for a bra, as shown and described.

DESCRIPTION

FIG. 1 is a perspective view of a bra showing my new design.

FIG. 2 is a front view of a bra.

FIG. 3 is a rear view of a bra.

FIG. 4 is a left side view of a bra.

FIG. 5 is a right side view of a bra.

FIG. 6 is a top view of a bra.

FIG. 7 is a bottom view of a bra; and,

FIG. 8 is a rear view of a bra, shown the open state of buckle. The broken lines in the drawings representing stitching are part of the claimed design.
